UNITED STATES PATENT OFFICE.

CYRUS S. OLDRYD, OF CINCINNATI, OHIO.

RAILWAY-TRACK AND RAIL FOR THE SAME.

1,391,574.

Specification of Letters Patent. Patented Sept. 20, 1921.

Application filed January 19, 1921. Serial No. 438,412.

To all whom it may concern:

Be it known that I, CYRUS S. OLDRYD, a citizen of the United States, residing at Cincinnati, in the county of Hamilton and State 5 of Ohio, have invented a new and useful Improvement in Railway-Tracks and Rails for the Same, of which the following is a specification, reference being had to the accompanying drawing.

10 My improvement relates particularly to railway tracks for use in mines and similar structures where tracks are to be laid to support cutting machines and loading machines and other working machines which 15 are to move forward as the work progresses, such forward movement requiring an extension of the track.

The object of my invention is to produce such an extensible track in a form which 20 will permit ready laying of the track while the work progresses.

If so desired, the entire track may be formed of the new rails herein described, or the track may be composed in part of 25 the ordinary T-form track rails now in use in mines and having a cross section similar to the larger rails now in use in tracks for steam railways.

The new rails herein described have three 30 important features: (1) the rails are reversible on their long axis, so that the part at one time resting upon the ground or floor may at another time be above and form the tread of the rail; (2) these rails are adapted to be so engaged by the wheels of the 35 working machines or mine cars as to hold said rails from spreading or otherwise shifting horizontally; and (3) the new rails are so formed as to be adapted to be joined 40 end-to-end to the ordinary track rails.

In the accompanying drawings,

Figure 1 is a plan of a part of a track embodying my improvement, parts being broken away;

45 Fig. 2 is a perspective view showing a fragment of the new rail and also a connecting or splicing block, used along with a fish-plate, for joining the new rail to an old or ordinary T-form mine track rail;

50 Fig. 3 is an upright section on the line, 3—3, of Figs. 1 and 5, looking in the direction of the arrow;

Fig. 4 is a section on the line, 4—4, of Figs. 1 and 5, looking in the direction of the arrow;

55

Fig. 5 is an elevation looking at the track toward the right as shown in Fig. 1;

Fig. 6 is a detail plan showing the meeting ends of two of my improved reversible or interchangeable rails.

60

Referring to said drawings A, A are ordinary T-form mine track rails, each having a head A¹, a web A², and a foot A³. W, W are ordinary car wheels, each having the usual flange, W¹, the tread of the wheel being adapted to rest on the head, A¹, of the rail while the flange extends downward over one side of said head.

65

B is a rail of the new form. For convenience in description, this will be called 70 the extension rail.

In cross section, this rail is in approximately the form of a letter S, assuming that the letter has been turned into the horizontal position. This rail consists of a middle upright web, B¹, two upright webs, B³, and two horizontal connecting webs, B², one of said webs connecting the web, B¹, with one of the webs, B³, and the other of said webs, B², connecting the web, B¹, with the other web, B³; the webs, B² extending along the edges of the webs which they connect. The free edge of each upright web, B³, is brought into the same plane with the outer face of the adjacent horizontal connecting web, in order that said edge and said face may rest on a tie or floor while the webs, B¹ and B³, are substantially upright and the upper face of the upper web, B², is approximately horizontal and adapted to constitute a tread for the wheels, W. And the upper face of the upper web, B², and the edges of the web, B¹, and the adjacent web, B³, are made of a width approximately 85 equal to the width of the head, A¹, of the rails, A. And the upright webs and the horizontal webs are so proportioned as to bring the upper face of the upper web, B², to the height of the upper face of the head, A¹, of the rails, A, in order that an ordinary 90 T-rail and one of the extension rails may 100 be placed end-to-end and form a continuous tread or running surface for wheels, W.

The lower web, B², and the lower edge of

the upright flange, B^3 , which is joined to the other horizontal web together form a relatively broad base for the extension rail, broader than the foot, A^3 , of the rail, A. 5 This gives the rail, B, a good setting on the tie or floor.

The rail, B, is symmetrical in cross-section and may be turned so as to place either horizontal web, B^2 , below. In either case, the 10 base of the rail is the same and the upper part is the same. Between the upright web, B^1 , and each upright web, B^3 , is a channel, one of said channels opening upward beside what is at the time the tread of said rail. 15 The flanges, W^1 , of the wheels, W, extend into the channel which opens upward.

Shifting of the rail toward the middle of the track is resisted by engagement of the flange, W^1 , with the middle upright web, 20 B^1 , and moving of the rail away from the middle of the track—"spreading"—is resisted by engagement between the wheel flange and the adjacent upright web, B^3 , said web constituting a guard for the wheels.

25 The extension rail, B, is placed endwise against the end of the T-rail, A, the upper web, B^2 , of the rail, B, being placed in alignment with the head, A^1 , of the rail, A. This brings the upward-directed web, B^2 , 30 toward the middle of the track, and thereby the channel which is to receive the wheel flange is placed between the tread of the rail and the middle of the track. The ends of the meeting rails are preferably supported 35 on a tie, T, which is preferably formed of flat metal having up-turned ends, T^1 .

The one form of extension rail will answer for either side of the track. Turning one of these rails end-for-end will bring the guard 40 web to the opposite side of the rail relative to the middle of the track.

The meeting ends of the rails, A and B, are coupled to each other by a connecting block, C, and a fish-plate, D. Fig. 2 shows 45 the connecting or filling block, C, in perspective. Said block comprises a part, C^1 , adapted to overlap a part of the rail, A, and of a part, C^2 , adapted to extend between the middle upright web, B^1 , and the upright web, B^3 , which is joined to the upper horizontal web, B^2 . The block shown by Fig. 2 is 50 adapted to be placed in the left-hand part of the track as shown in Fig. 1. The part, C^1 , of said block extends into the channel between the head, A^1 , and the foot, A^3 , at the outer side of the rail, A, and extends outward as far as the outer face of the adjacent 55 upright web, B^3 , of the extension rail, B. Thus a continuous upright seat is formed 60 for the fish-plate, D.

The web, A^2 , of the rail, A, has a horizontal, transverse aperture, A^4 , and the part, C^1 , of the block, C, has a horizontal, transverse aperture, C^3 , and the fish-plate, D, has 65 a transverse aperture, D^1 . Said three aper-

tures are in horizontal alignment with each other. A binding bolt, D^2 , extends horizontally through said three apertures and binds the rail, A, the block, C, and the fish-plate, D, to each other.

To the inner upright web, B^3 , of the rail B, at the side of said web which is toward the middle of the track is placed a web extension plate, E, said plate extending parallel to the fish-plate, D. The end of said plate, E, which is opposite the part, C^2 , of the block, C, has a horizontal, transverse aperture, E^1 , and each of the upright webs of the rail, B, has a transverse, horizontal aperture, B^4 , and the part, C^2 , of the block, 80 C, has a transverse, horizontal aperture, C^4 , and the fish-plate, D, has a transverse, horizontal aperture, D^3 . All of said apertures are in horizontal alignment with each other. A bolt, D^4 , extends through said apertures 85 and binds the extension plate, E, the rail, B, the part, C^2 , of the block, C, and the fish-plate firmly to each other. It is to be observed that this bolt is low enough to avoid interfering with the passing of the flange, 90 W^1 , of the wheels, W.

The up-turned ends, T^1 , of the tie, T, hold the meeting ends of the rails from moving away from the middle of the track. Similar ties are to be placed under the rails, A, at 95 as many places as may be deemed necessary to prevent said rails from spreading. Away from the joint formed by the meeting of the rails, A and B, there need be no ties to keep the rails, B, from spreading; for, as above 100 stated, the inner webs, B^3 , will be engaged by the wheel flanges to prevent movement of said rails away from the middle of the track.

The extension plates, E, are to serve for 105 guiding the wheel flanges when the wheels are on the rails, A, and approaching the rails, B.

In practice, the track leading to the working place is usually to be composed of the 110 ordinary T-rails A. At the working place, the extension rails, B, are to be laid to extend the track as fast as the work progresses, the working machine going forward and backward as needed during the operation of 115 the machine.

When the work has progressed far enough to leave back of the machine a sufficient stretch of track formed with the extension rails, B, track men may take up rails, B, 120 adjacent the rails, A, and substitute rails A, thus progressively extending the permanent or relatively permanent track.

When two extension rails, B, are placed end-to-end, they may be joined to each other 125 by two fish-plates, D, and two bolts, D^4 , the fish-plates being placed at opposite sides of the rails and extending over the joint formed by the meeting ends of the rails. (See Fig. 6.)

It will be understood that, if so desired, the entire track may be formed of my reversible extension rails.

It is to be noted that when what is being used as the upper side of the rail becomes worn or otherwise damaged, the rail may be turned to bring the lower side up.

I claim as my invention,—

1. A reversible railway track rail having at each side a single tread and a single web forming a wheel flange guard, said web being separated from said tread by a wheel flange channel, said channels being at opposite sides of the middle upright longitudinal plane of the rail, whereby either side of the rail may serve as base or top of the rail, substantially as described.

2. A reversible railway track rail having at each side a tread and a web forming a wheel flange guard, said web being separated from said tread by a wheel flange channel, said channels being in diverse upright planes and said channels being deep enough to be cut by a common horizontal plane, whereby either side of the rail may serve as base or top of the rail, substantially as described.

3. A reversible railway track rail having at each side a tread and a web forming a wheel flange guard, said web being separated from said tread by a wheel flange channel, said channels being in diverse upright planes and said channels being deep enough to be cut by the middle horizontal longitudinal plane of the rail, whereby either side of the rail may serve as base or top of the rail, substantially as described.

4. A reversible railway track rail having at each side a tread and a web forming a wheel flange guard, said web being separated from said tread by a wheel flange channel, said channels being at opposite sides of the middle upright longitudinal plane of the rail and said channels being deep enough to be cut by a common horizontal plane, substantially as described.

5. A reversible railway track rail having at each side a tread and a web forming a wheel flange guard, said web being separated from said tread by a wheel flange channel, said channels being at opposite sides of the middle upright longitudinal plane of the rail and said channels being deep enough to be cut by the middle horizontal longitudinal plane of the rail, substantially as described.

6. A railway track rail comprising three upright webs and a lower web connecting the middle upright web and one of the outer upright webs and an upper horizontal web connecting the middle upright web and the other upright web, the free edge of each outer upright web extending into the plane of the outer face of the adjacent horizontal web, the upright webs being of sufficient height to permit extending a bolt horizontally and transversely through the rail and leave between the upright webs clear courses for the wheel flanges, substantially as described.

7. A railway track rail of S-form cross section and comprising horizontal connecting webs and adapted to lie on one connecting web and the free edge of one side web, and the other connecting web forming a tread for the wheels and the other side web being directed upward and forming a guard for the wheel flanges, substantially as described.

8. A reversible railway track rail having at each side a tread and a web forming a wheel flange guard, the said web being separated from said tread by a wheel flange channel, whereby either side of the rail may serve as base or top of the rail, said rail being of such relative height as to allow space for a bolt to extend horizontally and transversely through the rail below the path of the wheel flange, substantially as described.

9. A reversible railway track rail having at each side a tread and a web forming a wheel flange guard, said web being separated from said tread by a wheel flange channel, whereby either side of the rail may serve as base or top of the rail, and said rail being of such relative height and said channels being of such relative depth as to allow the passing of a bolt horizontally and transversely through said channels, the parts of said channels between said bolt and the opening of the channels being of sufficient depth to provide a clear course for a wheel flange, substantially as described.

10. A railway track rail comprising three upright webs and a lower web connecting the middle upright web and one of the outer upright webs and an upper horizontal web connecting the middle upright web and the other upright web, the free edge of each outer upright web extending into the plane of the outer face of the adjacent horizontal web, the upright webs being of sufficient height to permit extending a bolt horizontally and transversely through the rail and leave between the upright webs clear courses for the wheel flanges, substantially as described.

11. A railway track rail approximately S-form in cross section and adapted to lie on one connecting web and the free edge of one side web and the other connecting web forming a tread for the wheels and the other side web being directed upward and forming a guard for the wheels, the relative height of said rail being sufficient to leave room for a bolt to extend horizontally and transversely through the rail clear of the wheel flange path, substantially as described.

12. A reversible railway track rail having at each side a tread and a web forming a wheel flange guard, said guard being separated from said tread by a wheel flange channel, whereby either side of the rail may serve as base or top of the rail, a bind-

ing member, and a bolt extending horizontally and transversely and clear of the wheel flange path through the rail and said binding member, substantially as described.

- 5 13. In a railroad track, the combination of a **T**-rail and an extension rail, said rails being placed end-to-end and detachably joined to each other and said extension rail being reversible and having at each side 10 a tread and a web forming a wheel flange guard, said web being separated from said tread by a wheel flange channel, whereby either side of the rail may serve as base or top of the rail, substantially as described.
- 15 14. In a railroad track, the combination of a **T**-rail and a plurality of extension rails, one of the extension rails being placed endwise against the **T**-rail and detachably secured thereto, and another extension rail 20 being placed endwise against the first extension rail and detachably secured thereto, said extension rails having at each side a tread and a web forming a wheel flange guard, said web being separated from said 25 tread by a wheel flange channel, whereby either side of the rail may serve as base or top of the rail, substantially as described.
- 30 15. In a railroad track, the combination of a **T**-rail and an extension rail, said rails being placed end-to-end and detachably joined to each other and said extension rail being **S**-form in cross section and adapted to lie on one connecting web and the free 35 edge of one side web, and the other connecting web forming a tread for the wheels and the other side web being directed upward

and forming a guard for the wheels, and a connecting block extending into the space between the head and the foot of the **T**-rail and into one of the channels of the extension rail, and bolts detachably securing said block to said rails, substantially as described.

16. In a railroad track, the combination of a **T**-rail, an extension rail having at each side a tread and a web forming a wheel flange guard, said web being separated from said tread by a wheel flange channel, whereby either side of the rail may serve as base or top of the rail, and a connecting 45 block extending into the space between the head and the foot of the **T**-rail and into one of the channels of the extension rail, a fish-plate applied over a part of said block and over a part of the extension rail, and means 50 for detachably securing said block and said fish-plate to said rails, substantially as described.

17. In a railroad track rail, two channelled rails placed end-to-end, one of said rails being reversible and **S**-form in cross section, a connecting member extending into one of the channels of the last-mentioned rail and into a channel of the other rail, and means 60 for detachably securing said connecting member to said rails, substantially as described.

In testimony whereof I have signed my name this 17th day of January, in the year one thousand nine hundred and twenty-one. 70

CYRUS S. OLDROYD.
